UNITED STATES PATENT OFFICE.

CLARENCE W. JOSLIN, OF CLEVELAND, OHIO, ASSIGNOR TO MECHANICAL RUBBER COMPANY, A CORPORATION OF NEW JERSEY.

DESIGN FOR A JAR-RING.

50,389.

Specification for Design.

Patented Feb. 27, 1917.

Application filed July 6, 1915. Serial No. 38,327. Term of patent 14 years.

To all whom it may concern:

Be it known that I, CLARENCE W. JOSLIN, a citizen of the United States, residing at Cleveland, county of Cuyahoga, and State of Ohio, have invented a new, original, and ornamental Design for a Jar-Ring, of which the following is a specification, reference being had to the accompanying drawing, forming part thereof.

The figure is a perspective view of a jar ring, showing my new design.

I claim:

The ornamental design for a jar ring, as shown.

Signed this 23rd day of June, 1915.

CLARENCE W. JOSLIN.
